SPRING ASSEMBLY

Mac Levine, Worcester, Mass., assignor to Webster Spring Co., Inc., Worcester, Mass.
Filed Aug. 5, 1963, Ser. No. 299,699
5 Claims. (Cl. 5—249)

This invention pertains to spring assemblies such as are employed in the seat portions of upholstered furniture.

In the construction of upholstered chairs, sofas, and so forth, the practice, at least up to recent years, has been to use a spring platform including a multiplicity of upright coiled springs for the support of the cushion or cushions upon which the user will sit. The customary procedure was to build this platform, by hand, into the frame of the chair or sofa. This was a slow operation, requiring skill and which, because of the increasing cost of labor, has made the construction of such upholstered furniture very expensive. In the attempt to facilitate this operation and thus reduce the cost, it has been proposed to provide prefabricated or "drop-in" spring platforms which were made up as independent units, for example by a spring manufacturer specializing in the preparation of such devices, and which were designed to be installed by the furniture maker as provided by the spring manufacturer, thus freeing the furniture maker from the troublesome manual operations involved in the installation of a built-in platform. Among such prefabricated platforms may be mentioned that disclosed in the patent to Levine, No. 2,910,114, dated October 27, 1959, which has proven commercially successful in so far as an individual unit of the patented device is concerned.

However, because the designers of furniture do not necessarily feel themselves restricted to such practical considerations as the availability of prefabricated platform units of the proper dimensions (although they have felt constrained to recognize a uniform front-to-rear dimension for furniture seats), the manufacturers of furniture, in attempting to adopt some of the designs offered to them and which, in other respects, might appear very desirable, have now found themselves faced with the necessity of ordering, from the makers of such prefabricated spring platforms, platforms custom-made to their particular requirements. This places an unwanted burden upon the manufacturer of such platforms. Not only must he recalculate the proper spacing of springs to make platforms which are of unusual lengths, but because of the demand of the furniture maker to obtain such a custom-made platform immediately when ordered, the platform builder may find himself obliged to employ additional help or pay for overtime labor in order to produce the desired off-sized platform within a short period of time. Such mode of manufacture is annoying and troublesome to the platform manufacturer and obviously means a high cost of the completed article to the furniture maker.

The present invention has for its object the provision of a novel method whereby a spring assembly may be made up to substantially any desired length, for example so as to fit a seat frame of arbitrarily fixed dimension and by the employment of a minimum amount of time and labor, and the provision of a novel spring assembly such as results from the practice of said method. A further object is to provide for the manufacture of spring assemblies of substantially any desired length, merely by the combination of standard parts so that the furniture manufacturer himself, if he so desire, may, according to the present invention, make up his own spring platforms to any desired length as required by the design which he wishes to follow. Thus, it is unnecessary for him to order

2

completed spring assemblies of unusual lengths from the spring manufacturer and eliminates the delays which are so often experienced in obtaining custom-made spring assemblies from an outside source.

Briefly stated, the above objects are attained, in accordance with the present invention, by providing prefabricated spring platforms within a range of widths wherein, for example, the narrowest or modular unit of the series fits the narrowest customary chair seat while each successive unit of the series differs in width from the next preceding one by a fixed amount referred to as the "modular difference," and connecting devices, for uniting adjacent assembled spring platform units, are provided in a range of lengths wherein the length of the shortest is but a relatively small fraction of the width of the modular spring unit and each successive connector of the series differs in length from the preceding one by a fraction of one inch, herein referred to as the "modular difference in length." By means of such a series of prefabricated spring platforms and connecting devices, it is possible for the furniture manufacturer, by assembling selected platforms and connectors, to build a spring assembly to fit a seat frame of almost any arbitrary length.

Other and further objects and advantages of the invention will be pointed out in the following more detailed description and by reference to the accompanying drawings wherein:

FIGS. 1, 2 and 3 are diagrammatic plan views of spring platforms differing from one another in length, in accordance with a fixed modular difference (much exaggerated, as shown) as provided by the present invention;

FIG. 4 shows a spring assembly comprising two of these platform units, each of the minimum length within the range provided;

FIG. 5 is a similar view showing an assembly made up of two units, each exceeding the minimum size;

FIG. 6 is a small scale diagrammatic view, in broken lines, showing the seat frame of a sofa of substantial length and illustrating how a spring assembly for such a very long and arbitrarily dimensioned frame may be made up by the practice of the present invention;

FIG. 7 is a horizontal section, substantially on the line 7—7 of FIG. 8, showing a single spring platform of a desirable type mounted in a chair seat frame;

FIG. 8 is a fragmentary diagrammatic front elevation showing two united spring platforms;

FIG. 9 is a fragmentary perspective view, to larger scale, showing a portion of the top frame of the two spring platforms, such, for example, as those of FIG. 7 which have been assembled and united by a spacer device and wherein the space between the top front members of the frames of the assembled spring platforms is so bridged as to provide the assembly with a top front edge which is of substantially uniform resiliency throughout its length;

FIG. 10 is a fragmentary plan view of the parts shown in FIG. 9;

FIG. 11 is a front elevation showing the connection between the top front members of adjacent platforms;

FIG. 12 is a section, to larger scale, on the line 12—12 of FIG. 11; and

FIG. 13 is a composite view illustrating connectors or spacers of a range of sizes.

Referring to the drawings, the character P²⁰ (FIG. 1) indicates a spring platform unit of the type which is desirably employed in accordance with the practice of the present invention. This unit comprises a top frame 23 and a bottom frame 24 (FIG. 8), each, in accordance with one desirable embodiment of the invention, being substantially rectangular and each consisting of stiff carbon steel spring wire which may, for instance, be of the order

of one-eighth of an inch in diameter, although the lower frame may, for example, be made of wire of one-quarter inch diameter in order to provide a stronger foundation. Each of these frames may consist of a single length of wire suitably bent to shape and having its ends welded or otherwise united, although if the frame be made of wire as heavy as one-quarter of an inch in diameter, it may be preferable to make it of suitable straight lengths, united approximately at the respective corners of the frame by welding or brazing. Interposed between the planes of these frame (which are disposed one over the other and in substantial registry), there are arranged rows of spiral springs S of the general type employed in upholstery work and these springs are securely anchored to the respective frames and to each other by any appropriate means, although as here illustrated the coils of the outer rows are secured to the top frame 23 (FIGS. 8, 10 and 11) by helical coils 25 of wire, while the several spring coils are connected at their upper ends by appropriate means, familiar to those skilled in the art (FIG. 5), to form a substantially horizontal supporting surface for a pad or cushion. The lower frame 24 (FIG. 7) desirably comprises longitudinally and transversely extending lengths of stiff wire secured, as by welding or otherwise, to the front and rear members and to the opposite side members respectively of the lower frame, and the springs are secured at their lower ends to the rigid supporting structure thus provided.

As diagrammatically indicated in FIG. 1, the front member 23 of the top frame is integrally joined at its left and right-hand ends to the side members $23a$ and $23b$ respectively, the latter extending rearwardly and being joined to the rear member $23c$.

With the understanding that the spring platform P^{20} is the narrowest of its series and thus constitutes the modular unit, the platform units P^{21} and P^{22} , shown in FIGS. 2 and 3 respectively, are of the same construction as the modular unit P^{20} except that they differ in transverse width, that is, from left to right, from the platform P^{20} by a definite difference in width, this difference, in accordance with the present invention, being a constant or "modular difference" between successive platform units. This modular difference may, for example, be a fraction of an inch. The platform units, as thus briefly described, may be of the kind disclosed in greater detail in the United States patent to Levine, No. 2,910,114, dated October 27, 1959, although it is not necessary, in accordance with this invention, that they be of precisely the construction described in said patent.

In FIG. 7 such a modular unit is shown as constituting the entire spring platform for a chair seat frame T and a desirable way of mounting such a unit in a seat frame is illustrated by way of example. However, since details of the mounting of the spring platform in a seat frame form no part of the present invention, such details are omitted.

Referring to FIG. 6, there is indicated diagrammatically a seat frame F , for example for a divan of substantial length, this frame comprising the rigid front and rear members 30 and 31 and the end members 32 . It may be understood for the purpose of the present discussion that this frame has been made by a furniture manufacturer in the adoption of some particular design or in accordance with the requirements of a customer, and that the distance between the edges 34 and 35 of the end members is arbitrarily fixed; for example it may be a distance of a certain number of feet and inches or even fractions of an inch.

Ordinarily, in accordance with prior custom, the manufacturer would either have proceeded to build up a continuous platform from end-to-end of the frame by hand labor, involving a slow and difficult process, or he would have ordered from the maker of prefabricated drop-in springs a single spring assembly of the exact length required for this particular frame. However, in accordance with the present invention, and assuming that the manufacturer of prefabricated spring platforms has adopted

the teaching of the present invention, there will be available to the furniture manufacturer platform units of a substantial range of sizes in which successive units differ from each other by a fixed amount, as here termed the "modular difference." Furthermore, in accordance with the present invention, the spring manufacturer will have provided devices for connecting adjacent platform units in a range of lengths also differing from each other according to an established modular difference. By means of this range of platform units and connectors, it is readily possible for the furniture manufacturer to build up a spring assembly by a suitable combination of platform units and connectors which will be within a tolerated approach to the length of the frame F regardless of the length of the latter.

Having provided himself with the proper assembly of platform units and connectors, he will then arrange them in any convenient order as, for example, suggested in FIG. 6, wherein the two endmost platform units are of the narrowest width within the range, while the intermediate units are of larger sizes. Likewise, the connectors are of such different lengths so as to make up the exact length of the desired assembly.

The connectors 26 (FIG. 13) are formed of stiff wire, for example of a stiffness approximating that of the top frame of the unit, and in a range of lengths wherein, for example, the shortest or modular connector is 2.5 inches in length (measured between the centers of curvature at its opposite ends) and the modular difference between successive connectors is 0.25 inch for example.

These connectors are furnished with their ends bent to a hair-pin loop so that they may be slipped over the side members $23b$ and $230b$ (FIG. 10) of adjacent units P^1 and P^2 and then have their ends closed together so that they grip the members $23b$ and $230b$ of the respective units, thus holding the latter in properly spaced position. However, the connector 26 does not grip the frame members $23b$ and $230b$ so as to prevent relative up and down motion of said frame members. Thus, while normally the connector 26 may be substantially horizontal, as indicated in FIG. 11, the frame member $23b$ may move downwardly relatively to the member $230b$ if downward force be applied near member $23b$, while, on the other hand, if the force be applied in a downward direction near the frame member $230b$, the latter may move down relatively to the frame member $23b$. Thus, these connectors 26 provide hinge connections between adjacent spring platforms so that, although the platforms are connected, the downward yield of the upper surface of the assembly is not substantially different at the space between the platforms than at points directly above the individual platform.

In order to provide continuity between the front members $23b$ and $230b$ of the top frames of adjacent platforms P^1 and P^2 , the present invention provides for the arrangement of a bridge member B (FIGS. 9, 10 and 11), desirably consisting of a rectilinear length of stiff spring steel wire, for example like the wire forming the top frame member and which is of a length which may, for example, be approximately three times the width of the space between adjacent platforms. Thus, the bridge member overlaps the front members $23b$ and $230b$ of the adjacent platforms for a substantial distance and these overlapping portions are securely bound to the frame members $23b$ and $230b$, for example by the same helical coil 25 which secures the upper ends of the spiral springs to the top frame.

As shown in FIGS. 4 and 5, for example, the connecting members 26 (which also constitute spacer and hinge members) are spaced apart from front-to-rear, four such spacers being shown in FIGS. 4 and 5. The foremost of these spacers, designated by the character $26a$ (FIG. 10) is closely adjacent to the front members $23b$ and $230b$ of the adjacent spring platforms so that its midportion is substantially in contact with the midportion of the bridge member B . These members $26a$ and B are united at this point by a metallic clip 40 (FIGS. 9 and 10).

which may, for example, be a length of stiff sheet steel which is curled about the parts 26a and B and firmly compressed so that its ends overlap and rigidly unite the parts 26a and B.

With this arrangement the forward edge of the top frame member functions substantially as though it were continuous and uninterrupted from one end of the assembly to the other and when the pad or cushion has been applied to an assembly built up in this manner, the fact that it consists of a plurality of independent prefabricated platforms, which in some instances may be spaced apart a distance of several inches, is not perceptible to the user.

Merely by way of example, suppose that the modular difference between successive platforms be

$$\frac{X}{40}$$

where X (the width of the narrowest platform) is 20 inches, then the width of successive platforms might be expressed as X;

$$X + \frac{X}{40}; X + \frac{2X}{40}; X + \frac{3X}{40}; X + \frac{4X}{40}$$

etc., which numerically becomes 20 inches; 20.5 inches; 21.0 inches; 21.5 inches; 22.0 inches; etc.

If now the modular difference in the length between successive sizes of connecting devices be

$$\frac{X}{10}$$

and X (the length of the shortest connecting device) be 2.5 inches, then the lengths of successive sizes of connector may be expressed as X;

$$X + \frac{X}{10}; X + \frac{2X}{10}; X + \frac{3X}{10}; X + \frac{4X}{10}$$

etc., or numerically 2.5 inches; 2.75 inches; 3.00 inches; 3.25 inches; 3.50 inches; etc.

It will be readily be apparent that by selecting platforms of suitable width from the available series and connectors appropriate lengths it becomes possible to build up a spring assembly which will fit a seat frame of almost any length including lengths involving fractions of an inch. It is further within the purview of the invention to provide a basic range of sizes of platforms beginning with the narrowest and extending, for instance, to include one which is double the width of the narrowest and then (to avoid the necessity for providing a continuous series extending up to a high multiple of the narrowest or modular unit and also reducing the number of units required to make up a long spring assembly), to start a new series whose narrowest or modular unit would be a substantial multiple of the narrowest or modular unit of the first series and on the basis of this new modular unit to develop a new series, but preferably using the same modular difference.

The above numerical values are suggested merely by way of example and as illustrative of the basic principle of the invention but without any intent to limit the scope of the invention to these particular values.

By the means and method of procedure thus provided it is readily possible for the furniture manufacturer to provide himself with spring assemblies of almost any desired length and with far less delay and at substantially less cost than has been heretofore possible while following customary prior practice.

While one desirable embodiment of the invention has herein been disclosed by way of example, it is to be understood that the invention is broadly inclusive of any and all modifications, substitutions of materials, and order of methods steps which fall within the terms of the appended claims.

I claim:

1. A spring assembly for use in a furniture seat frame of the customary front-to-rear dimension and of arbitrary

length, said assembly comprising a plurality of independent prefabricated spring platforms arranged side-by-side in said frame, all of said platforms being of the same front-to-rear dimensions, and connecting means so permanently uniting adjacent platforms as to provide an assembly of invariable length and such as to fit said seat frame, and wherein the assembly has a horizontal supporting surface whose forward edge functions substantially as though it were continuous and uninterrupted from end-to-end of the assembly.

5 2. A spring assembly according to claim 1, wherein each platform includes rows of coiled springs and upper and lower open frames of stiff spring steel wire, each frame having front members and side members extending rearwardly from said front member, and wherein the connecting means, whereby adjacent platforms are united, comprises hinge elements which connect the proximate side members of the frames of adjacent platforms and hold adjacent platforms in relatively fixed relation, bridge members, each of a stiffness approximating that of the wire constituting the platform frames, extending across the space between the adjacent ends of the front members of the upper frames of adjacent platforms and overlapping and being connected to said front members, and means rigidly connecting the midportion of said bridge element to that one of the hinge elements which is the nearest to the top frame of said adjacent frames.

10 3. A spring assembly for use in a furniture seat frame of arbitrary length, said assembly comprising, in combination, a plurality of individual prefabricated spring platforms, each having an upper and lower frame of stiff spring steel wire, each of said upper and lower frames including a substantially rectilinear front member and side members extending rearwardly from the front member, rows of coiled springs interposed between the upper and lower frames of each platform, and means connecting the rows of springs to the platform frames, the front-to-rear dimension of all of the spring platforms being the same, spacer devices uniting the side members of the frames of adjacent platforms and holding the platforms in spaced relation, the foremost of said spacer devices being closely adjacent to the front members of the upper frames of the platforms which it unites, and a bridge member comprising a substantially rectilinear length of stiff spring wire extending across the space between the front members of the upper frames of adjacent platforms and being secured to and overlapping each of said front members, and means fixedly connecting the midportion of said bridge member to said foremost spacer device.

15 4. A spring assembly for use in a furniture seat frame of arbitrary length and of standard front-to-rear dimensions, said assembly comprising a plurality of individual prefabricated seat platforms, the front-to-rear dimension of all of said platforms being the same and proper for use in the aforesaid seat frame, some of said platforms differing in width from others in accordance with a fixed modular difference, means, comprising spacer devices, uniting adjacent platforms, some of the spacer devices differing in length from others in accordance with a fixed modular difference, the platforms and spacers comprised in said assembly being such that the completed assembly is of a fixed length such as to fit within the aforesaid seat frame, the means for uniting adjacent platforms being such that the forward edge of the assembly offers substantially the same degree of resistance to downward pressure in the space between adjacent platforms as at other portions of the supporting surface of the assembly.

20 5. That method of making a spring assembly for use in a furniture seat frame of arbitrary fixed length and standard front-to-rear dimension which comprises as steps: providing a reserve supply of prefabricated spring platforms each of standard front-to-rear dimension but which vary from one another in width according to a fixed modular difference; selecting from among said platforms a plurality such that their collective length is less than that of the desired assembly by an amount which is a fraction of

the width of the platform of least width among those provided; providing a reserve supply of spacer devices, including spacer devices which vary in length from one another according to a fixed modular difference; so spacing the selected platforms apart that the distance between the outer edges of the endmost platforms equals the desired length of the assembly but in selecting the platforms to constitute the assembly, so choosing them that by the use of spacer devices, selected from among those provided, the spacing of adjacent platforms, when united by the chosen spacer devices, is such that the completed assembly fits within the seat frame; so connecting adjacent platforms

5 by means of the selected spacer devices as to preserve the spacing between them; and securing a bridging element to each pair of adjacent platforms so as to provide the assembly with an uninterrupted forward upper edge of approximately uniform resiliency from end-to-end.
